Application February 27, 1947, Serial No. 731,173

5 Claims. (Cl. 101—426)

1

This invention relates to photo reproduction and particularly to processes and apparatus for producing a fairly large number of prints.

Straight photographic processes are inefficient and unnecessarily expensive when the number of reproductions exceeds 100 or 200, particularly in the case of color reproductions. On the other hand, photoengraving and photolithographic methods of color reproduction require expensive equipment whose cost is not warranted unless the total number of reproductions exceeds 5,000 or 10,000, say, in each case. The primary object of the present invention is to provide a process and apparatus for efficiently producing reproductions, particularly color reproductions, where only 1,000 or 2,000 prints are required. Adequately to satisfy the large market for such a printing process, the process itself must be a rapid and relatively inexpensive one. Of course the invention is applicable even when the number of prints required is larger or smaller than this particular range.

A further object, particularly of certain embodiments of the invention, is to provide a printing process in which coloring material is applied directly to paper, either as a halftone pattern or as a continuous-tone pattern, in accordance with a continuous-tone negative or positive transparency without the intermediate step of making a halftone negative.

The various embodiments of the invention described below and in co-pending applications referred to below, have individual advantages such as simplicity, rapidity and ease of operation, etc., each of which constitutes an object of the invention.

According to the invention a picture to be reproduced is scanned by a line proceeding sideways over the whole area of the picture at once in counter-distinction to ordinary scanning procedures in which a dot scans the picture a line at a time. It is well known that quality reproduction of pictures requires a certain number of lines per inch distinctively reproduced, but the number of lines depends on the size of the picture. For example, there is no point in using a fineness of 150 lines per inch in the production of a billboard. For the sake of definiteness, a limit of acceptable quality will be here taken as that represented by 50 lines in the total width of the picture. Fewer lines is considered unacceptable for most purposes. The line which scans the picture according to the invention, is made up of at least 50 small juxtaposed photosensitive elements, and the direction of scanning is at an angle, either a right angle or an acute angle, to this scanning line. The picture to be reproduced will be either a positive or a negative record, the

2

final reproduction being a positive, of course. The term "reproducing" is intended to mean both the production of a positive from a positive, or the production of a positive from a negative. The line of elements is, of course, made up of discrete and usually slightly separated elements. Just as there is an equivalence between contact and projection printing in photography, the scanning may be by projection through an optical system or by having the elements effectively in contact with the record. Each element of the scanning line produces a track and, in accordance with the above definition of minimal quality and definition, the width of each track must be less than two per cent of the width of the picture. Furthermore, the total width of all the scanning tracks must be at least equal to the width of the picture in order to encompass the whole picture by a single scanning operation.

20 Synchronously with the scanning of the picture, an image receptive sheet, such as a sheet of paper to receive ink or a photosensitive layer, is scanned with a corresponding number of juxtaposed density control elements. When this invention is applied to the making of enlarged pictures, for example, the density control elements are considerably larger than the photosensitive elements which scan the picture, but there is still a one for one correspondence between density control elements and photosensitive elements. Each density control element may be a valve or other means for controlling the deposition of ink, or it may be a valve for controlling the quantity of radiant energy falling on a sensitive medium. In accordance with the invention, each density control element is operated according to the response of the corresponding photosensitive element. In this way, a whole picture is scanned in a single sweep and a single print is made relatively rapidly.

30 40 Thus there is eliminated one of the main objections to prior scanning processes in which the picture is scanned a line at a time.

It is not necessary that the scanning be exactly at right angles to the lines of elements, and it is preferably at an acute angle since an oblique arrangement of the photosensitive elements simplifies the manufacture in some instances, especially when the elements are very small ones. Another embodiment of the invention having the same advantage of permitting easy manufacture of very small elements, employs a zig-zag line of elements.

A preferred embodiment of the invention employs as its photosensitive elements small fluid-containing cells, in which the expansion of the fluid in the cells controls the deposition of ink on a paper. A small capillary leads from each cell to the point at which the ink is deposited on the

paper. In one form of this embodiment, the whole cell and capillary are filled with ink, but preferably the cell is filled with a gaseous medium or other material having a high coefficient of expansion, which material in turn forces the ink from the capillary.

Cross reference is made at this point to a photoelectric embodiment of the invention described in co-pending application, Serial Number 731,372, filed concurrently herewith, by C. Q. Glassey, now U. S. Patent 2,487,865. In another alternative a relief image is scanned by a line of tactile elements to control corresponding ink depositors or other density control elements. Reference is also made to an application of thermal expansion cells to printing a whole area at once rather than by scanning, which areal block is described in copending application, Serial Number 745,019, filed April 30, 1947, by C. Q. Glassey, now Patent No. 2,543,013 dated February 27, 1951. This latter case describes a number of methods of making expansion cells which may be used alternatively to the one described herein for either a line or an area of cells.

In the application of thermal expansion cells to the above described scanning arrangements, it is preferable to deposit one line of ink, either in halftone dots or with a controlled amount of spreading of the ink to give a continuous-tone effect, and then to refill the capillaries and to cool the cells before repeating the operation to print the next line. That is, the cells are arranged in a line onto which an image of the picture to be reproduced is projected, either by an optical system or by contact printing. The heat in the image is transferred to the cells differentially in accordance with the image, which heat causes the fluid in the cells to expand, forcing proportional amounts of ink from the capillaries onto the adjacent paper. The image is then cut off momentarily, the cells are allowed to cool, the working pressure in the cells is reestablished, and the capillaries recharged with ink. During this interval the picture is moved the width of the scanning line, and the paper is correspondingly moved to receive the next line of ink depositions. The light is turned on by a suitable shutter arrangement for the necessary interval of time to deposit the ink properly, and then the whole cycle is repeated.

Obviously this line of cells is made up of very small cells, especially when there are 150 cells to the inch, for example. These cells may be made and assembled in various ways, but one particularly simple method involves forming a relief matrix, for example by electrodeposition on pre-determined areas, and then by stripping plastic sheets from this matrix with the cell structure incorporated as intaglio in the plastic.

Registration is always a problem in color printing processes, and in the present invention, it can be obtained by any of the usual careful methods used in other color printing processes. However, one particularly applicable system involves four-color printing simultaneously, two colors being printed on each side of a thin transparent pellicle, which may be later laminated to an opaque white support.

Other advantages and features of the present invention will be apparent from the following description of various preferred embodiments thereof when read in connection with the accompanying drawings, in which:

Fig. 1 is a perspective view of one embodiment

of the invention which illustrates the general principles thereof.

Fig. 2 is an enlarged detail of one feature of Fig. 1.

Figs. 3 and 4 illustrate preferred arrangements of the line of elements in Fig. 1.

Fig. 5 is a greatly enlarged front view of elements according to a preferred embodiment of the invention.

Fig. 6 is a vertical cross-section of the same elements, also greatly enlarged.

Figs. 7 and 8 are respectively plan view and vertical section, both greatly enlarged of a slightly different embodiment of the invention.

Figs. 9 and 10 are respectively a greatly enlarged vertical section and a perspective view of a preferred embodiment of the invention.

Fig. 11 is a diagrammatic vertical section of an embodiment of the invention.

Fig. 12 similarly illustrates another embodiment of the invention.

Figs. 13 to 16 illustrate a preferred method of manufacturing expansion cells such as illustrated in Figs. 5 to 12.

Fig. 17 is a greatly enlarged perspective view of a preferred arrangement of expansion cells for the invention.

Figs. 18 and 19 are respectively front and side elevations of a preferred form of printing press employing one embodiment of the invention.

Fig. 20 illustrates a detail of the carrier belt of Figs. 18 and 19.

For clarity, unessential details have been omitted from Fig. 1. In this figure a color transparency 30 is moved as indicated by the arrow 31, by means not shown, under a triple scanning line provided by three lamps 32, red, green, and blue filters 33 and cylindrical lenses 34. The broken line 36 indicates the red line as focused on the transparency 30. The necessary light shields for confining the scanning beams to their respective paths are not shown in the drawing since they would confuse the illustration. The light passing through the transparency 30 impinges on a row of photosensitive elements 38 which are shown as photoelectric or selenium cells manufactured in accordance with Serial Number 731,372, now U. S. Patent 2,487,865, Glassey, mentioned above. Alternatively, these photosensitive elements may be expansion cells as described in connection with Figs. 5 to 20 of the present application. For acceptable quality there should be at least 50 such cells in the total width of the transparency 30. 50 to 150 lines per inch gives satisfactory reproduction for many purposes.

The reaction of the photosensitive elements 38 is used, according to the invention, to control the deposition of ink on a strip of paper 40, which is moved as indicated by arrow 41 synchronously with the movement of transparency 30. This control of ink depositing elements 42 is illustrated schematically by connecting wires 43.

Various direct control arrangements for the ink depositing elements may be used, such as the differential heating of bi-metallic pen orifices in accordance with the current from photoelectric or selenium cells. However, I prefer to employ electrostatic repulsion of ink as illustrated in Fig. 2. Any ink whose vehicle has a relatively high electrical resistance is subject to electrostatic repulsion from a charged point. Many, if not most, inks have this property. In Fig. 2 the individual elements 46 are insulated

from each other by insulating layers 41, and each element comes to a relatively sharp point 48. The space 50 between the points is filled with ink and normally this ink is flush with the end of the points 48. The charge on the particular point 51, however, is sufficient to repel some of the ink which thus forms a drop 52, which moves away from the point 51 and over to a layer 40 of paper which is carefully held just a short distance below the points 48. I prefer to operate this embodiment of the invention intermittently wherein a line of the transparency is scanned, the ink corresponding to that line is deposited, and then the whole press is reset to print the next line, the transparency being moved the width of one line, an inking member being applied to the pen points, and the paper to be printed being moved one line. As illustrated, the transparency 30 should be a negative in order to produce a positive final print. Continuous deposition is possible but adequate quality control is not so easily assured.

The manufacture of the photosensitive elements in a line is somewhat difficult because of the small size of the elements, and therefore, it is preferable, as illustrated in Figs. 3 and 4, to have this line oblique or zig-zag. The width of the track scanned by each element is still the same size as it was, but more space is provided around each element to permit greater rigidity of the supporting members. Both the oblique line and the zig-zag line are still referred to as a line of elements, and the direction of scanning is said to be at an angle to this line. In Fig. 1 the direction of scanning is at a right angle, in Fig. 3, it is an acute angle, and in Fig. 4 it is alternately acute and obtuse having two values supplementary to each other.

A highly preferred embodiment of the invention makes the photosensitive elements and the density controlled elements as a single unit. The light responsive element is simply a small cell containing a fluid whose expansion under the radiant energy is the response of the element. As illustrated in Fig. 5, such a cell 60 is provided with a capillary 61 to an orifice 62 from which ink is ejected to deposit on the paper being printed. A plurality of such cells 60 are juxtaposed, perhaps 150 to the inch, and each is provided with a heat absorbing cover 63. As before, it is preferable to employ intermittency in the scanning so that the ink cells are re-charged after each is printed. A simple arrangement for doing this is shown in Fig. 6, in which the ink 65 in the cells 60 is supplied through a tube 66 from an ink reservoir 67. After one cycle of printing is completed, the paper 70 is moved as indicated by arrow 71 and the transparency 72 is synchronously moved as indicated by the arrow 73. The valve 75 is opened, allowing ink to flow into the cell 60, filling the capillary right down even with the orifice 62. The valve 75 is then closed, and the printing light, as indicated by arrows 76, is then turned on, for example by opening a shutter. This light passes through the transparency 72 and differentially heats up the cell 65 in accordance with the image in the transparency. This causes ink to be ejected from the orifice 62 and deposited on the paper 70, after which the cycle is repeated.

Figs. 7 and 8 show a slightly different embodiment of the invention in which the expansion cells 80 are on the top of a printing bar 81, and

the capillaries 82 extend from the cells down through this bar to reach the printing surface 83. The upper surface of the cells is covered by transparent plate 84, and the supply channels 85 extend to the side of the bar 81, whereat they alternately connect to and are cut off from ink supply channels 87. These ink supply channels are carried in blocks 88, which are sprung-urged against the bar 81 by springs 89. The periodic printing operation requires the bar 81 to be moved out of contact with the paper 83, and at the same time the ink channels 87 to be connected to the cells 80. In Fig. 8 the right hand side of the figure illustrates one part of the cycle, whereas the left hand illustrates another part of the cycle, and in practice both sides are either in the up or in the down position at any one time. The motion of the various members is provided by means not shown in this particular figure. An alternative arrangement is shown in Fig. 9, which has the advantage that only the printing bar 91 need be moved. That is, the bar 91 is moved into contact with or very near the paper 92 for printing and the image light indicated by arrows 93 is turned on, expelling the ink from the cells 94 through the orifices 95. The bar 91 is then raised out of contact with the paper bringing the cells 94 into contact with the supply reservoirs 96, during which time the light 93 is cut off by a suitable shutter. This operation is illustrated in perspective in Fig. 10 wherein light from a lamp 100 illuminates a narrow band 101 of a transparency 102. This line of light is focused by a lens 103 on the upper surface 97 of the printing bar 91, causing ink to be printed on the paper 92. The light is then cut off by a shutter 104, and simultaneously the printing bar 91 is raised by a cam 105 coupled to the shutter 104 to move synchronously therewith. The cam 105 is to one side of the paper web 92 so that it raises only the printing bar 91 and does not raise the paper at the same time. This raising of the printing bar 91 brings the expansion cells into contact with the ink supply 106, which is supplied through channels 96. At the same time the transparency 102 and the paper 92 are moved forward the width of the scanning slit. Then the cam 105 lowers the printing bar 91 into contact with the paper, the shutter 104 opens and light falling on the surface 97 causes the ink to print on the paper, after which the cycle is repeated. The transparency 102 is shown flat for clarity, but in practice it is wrapped on a cylinder so that the printing operation is continuously repeated making a large number of prints on the roll of paper 92.

Before describing preferred embodiments in which the expelling medium is different from the ink being expelled, I wish to point out how the rate of operation of the invention is computed for the simple ink filled cells illustrated in Figs. 5 to 10. The following data is given for a 300 line per inch picture and for a printing source which in the exposure time allowed gives a 5° C. rise in temperature through the least dense portion of the negative, that is, the maximum temperature increase is 5° C.

The volume of each cell such as shown in Fig. 5 is approximately .006" x .010" x .004", which when converted to cubic centimeters equals 3.75×10^{-8} cc. Thus from each cell containing an alcoholic ink about 1.9×10^{-8} cc. of ink is expelled. The total volume of ink expelled from the 2100 cells comprising a seven

inch line, not counting the differential reduction due to the density of the image is about 4×10^{-5} cc. The heat absorbed by a single cell to raise the temperature of the alcohol 5° C. is about 9×10^{-6} calories which in turn works out to .019 calories for the 2100 cells.

These figures correspond to the usual amount of ink deposited in printing. That is, the maximum ink expelled from a cell is equivalent to a square of ink .003" x .003" x .0001".

The length of the capillary which is emptied when this ink is expelled depends of course on the diameter of the capillary and also on the expansion thereof. For example, a capillary .00004" in diameter will expel a length of ink equal to 0.8 inch whereas one .0003" in diameter will only expel .016" of ink from the tube. Although a long capillary travel favors accurate rendering of density variations, it is easier to make the larger diameter capillaries. The capillaries need not be highly regular or uniform in section. Thus without going to inconveniently intense light sources, it is possible to cut exposure time per line to .001 second, but I prefer to use somewhat less intensity and slightly longer printing time.

The coefficient of expansion of inks is not as high as that of certain other liquids, solids, and particularly gases. Therefore, for higher speed operation, I prefer to use a gaseous medium in the expansion cells. One arrangement for doing this is illustrated in Fig. 11, wherein the expansion cell 110 is normally at atmospheric pressure when the valve 111 is open as shown and the shutter 112 is closed so that no light from the object 113 through the lens 114 falls on the cell surface 115. In this condition the capillary 117 connected to the cell 110 is also connected to an ink reservoir 118, which is at atmospheric pressure since the valve 119 is open. The capillary attraction of ink from the reservoir 118 to the orifice 121 is augmented by a slight vacuum applied through a valve 122 and an overflow pipe 123 right at the orifice. Preferably this vacuum is arranged so as to bring the ink quickly down to the orifice but not sufficient to draw off any appreciable amount of ink during this operation. The valves 111, 119, and 122 are then all closed and the shutter 112 opened so that the image falls on the expansion cell 110. Since the valves are all closed, the expansion of the gas in the cell 110 forces ink from the orifice 121 onto the printing paper 125. The cycle is then repeated by closing the shutter 112 and opening the three valves.

This gas cell type of printing is applicable to the printing press shown in Fig. 10 by using an arrangement such as shown in Fig. 12. During printing, light as indicated by arrows 130 passes through a transparent or heat transmitting plate 131 to cause the medium in the cells 132 to expand, forcing ink from the orifices 133. The printing bar 134 is down during this operation so that the supply tubes 135 are cut off by the face 136 of the ink supply channels 137. After the printing part of the cycle is completed, the bar 134 is raised away from the paper to the position indicated by the broken lines 138. In this position the cells 132 are connected directly to the atmosphere through openings 139 and the capillaries are connected through tubes 135 to the ink supply 140 in the ink supply channels 137.

There are many ways in which the small cells may be manufactured, but one of the least expensive and most satisfactory methods involves printing and electroforming of a matrix, from

which the cells are cast by simple molding operations. Such an arrangement is illustrated in Figs. 13 to 16. A base plate 145 is first printed by any suitable printing method with a spot 146 and a line 147 of a conducting medium, such as silver. Photographic processes may be used for depositing the silver as a spot and a line corresponding to each cell. The silver is then copper plated by electrolytic deposition until the line is built up to a height equal to the desired capillary thickness, as illustrated by 148 in Fig. 14. The plate 145 is then withdrawn from the electrolytic solution to the point indicated by broken line 150, so that only the spot 146 remains in the solution. Copper deposition is continued until a high bump 149 is formed on each spot 146. This matrix, consisting of plate 145 and the copper pattern formed thereon, is then coated with a suitable transparent plastic 151, which covers the strip 148 but does not quite cover the top of the bump 149. If any plastic does coat on the bumps 149, this is removed by a light hand-buffing before the plastic is stripped from the mold. A pair of such strips 152, after being stripped from the mold, are placed in register so that an expansion cell 153 is formed, corresponding to the holes through both strips, and the capillary 154 is formed by the line in the upper of the two strips. These strips are then cemented securely to a plate 155, which has been perforated with a row of perforations 156 corresponding to the cells. The front surface of the cell is covered by a transparent strip 157 cemented to the bottom of the lower strip 152. The cement 158 used in this case is sufficient to fill the small groove 159, which exists in the lower strip by reason of its similarity to the upper strip in which the corresponding groove forms the capillary required. One eminently satisfactory way of assuring register between the plate 155 and the strips 152 is shown in Fig. 16 in which the plate 155 is made first and the plate 145 is made from it photographically by exposing through the orifice 156 on to a photosensitive layer 160. The exposure at the point 161 is continued until a considerable size spot is fogged and then the plate 145 is moved steadily and fairly fast under the orifice 156 so that lines leading from each spot to the edge 30 of the plate are exposed, eventually to form the lines 147.

Fig. 17 is included to show a zig-zag arrangement of the expansion cells 165 and a corresponding zig-zag arrangement of the orifices 166. With this arrangement the cells completely cover the length of the scanning line. That is, the width of the cell 167, as indicated by broken lines 168, is exactly equal or even slightly greater than the space between the cells 169. Too much overlapping would reduce the definition of the finished print, whereas too much space between the cells reduces the efficiency of the printer.

Figs. 18 and 19 illustrate a four-color printer for printing simultaneously, according to the present invention, from four color separation transparencies 175. These four transparencies are carried by an Invar belt 176, which is driven by rollers 177 over a series of rollers 178, all inside a large housing 180. Where the color separation transparencies are all film, the preferred method of assuring proper register is to register all of the films one on top of the other and then to perforate all four of them. The films are then mounted on the belt 176 by properly located pins carried by the belt 176. Alter-

natively, and preferably, glass plates are used for the color separation records, and in this case the plates are provided with registration marks shown as crosses 181 in Fig. 20, which registration marks are accurately located with respect to perforations 182 in the Invar belt 176. The plate as indicated by broken lines 183 is then clamped in place by suitable clamps 184. The registration of the lower two transparencies 175 is "advanced" relative to that of the upper two to allow for the offset of the corresponding printing stations 211 to be described later.

The purpose of using Invar as the supporting belt is to insure maintenance of register throughout a long run of, say, 5,000 prints, by avoiding temperature effects on the length of the belt. The four color separation records 175 are illuminated a line at a time by two lamps 190 and 191. From each side of each lamp a beam of light passes through a spherical lens 192 and a cylindrical lens 193 to be reflected from a plane mirror 194 and to form a line of light 195 on the color separation record 175. The housing 180 is shielded from each lamphouse by windows 197. These windows 197 may have a predetermined relative density or may be in the form of density wedges to permit color balance adjustment of the printer. The intensity of the lamps are controlled respectively by rheostats 200 and 201. Photoelectric cells 202 and 203 are provided adjacent to each lamp to permit accurate control of the relative intensity of the two lamps throughout the printing operation. The connections to these photoelectric cells are not shown since they are not an essential part of the present invention, but the control may be either manual operation of the rheostats 200 and 201 in accordance with meter readings, or may be automatic. The lamphouses are cooled by fans 205 and an insulation layer 206 is provided to keep the heat of the lamphouse from unnecessarily being transmitted to the printing chamber.

Light from the color separation records 175 is then focused by lenses 210 to form a line of light on rows of juxtaposed expansion cells 211, in accordance with the invention. The lenses 210 are shown as simple positive elements for clarity, but actually, highly corrected lenses are used. The details of the expansion cells 211 are so small that they cannot appear in this Fig. 18 but such details are illustrated in Figs. 5 to 12. A supply roll 220 of a transparent pellicle feeds a strip of material between two pairs of the ink depositing units 211. A motor 221 through a gear 222 and gears 223 and 224 synchronously drives the pellicle 225 and the Invar belt 176. Two colors are deposited on each side of the pellicle which then passes over a diagonal roller 230 and out of the box through an aperture provided therein, particularly as shown in Fig. 19. Usually an illuminator 231 as shown by broken lines in Fig. 19 is provided for quick inspection of the picture 232 on the pellicle as it passes from the printer.

After each print is made the Invar belt is returned to the starting position by disengaging the gear 224 from the gear 222. In the arrangement shown, this is performed manually, but a simple direct gearing arrangement may be employed for quickly driving the Invar belt 176 back to its starting position between the making of successive prints. Furthermore, in the arrangements shown relatively quick drying inks are used which permit the use of rollers engaging

the full width of the pellicle. Obviously rollers which engage only the edges of the pellicle are used with more slowly drying inks. The pellicle, after inspection, is laminated to any opaque white support desired, such as paper. To permit a new set of color separation negatives to be mounted on the Invar belt 176 and to permit a new supply roll 220 of pellicle to be inserted, the wall 240 of the housing 180 is removable as indicated by attaching screws 241.

Having thus described the preferred embodiments of my invention, I wish to point out that it is not limited to these structures but is of the scope of the appended claims.

15 I claim:

1. The method of reproducing a picture which comprises filling with ink a line of juxtaposed capillary orifices in a solid block, each connected to a fluid-filled cell, the cells also being in line, 20 illuminating a line of a negative of the picture in printing relation to the line of cells, exposing the cells by light from the line of the negative to heat the cells thereby causing expansion of the fluid and emission of ink from the orifices, 25 receiving the emitted ink on an ink receptive support, and periodically replenishing the capillary orifices with ink while synchronously scanning the negative by the line which exposes the cells and the support by the line of orifices.

30 2. The method according to claim 1 in which said fluid in the cells is solely ink, contiguous with the ink in the capillary orifices.

35 3. A printing device comprising a block containing a plurality of small juxtaposed ink filled cells each including an ink filled capillary extending to an orifice in the printing surface of the block, the orifices forming one and at most two single straight lines, means for filling the cells with ink, means for closing the cells completely except for said capillaries and means for exposing the so closed cells to a line of an infrared image.

40 4. A printing device comprising a block containing a plurality of small juxtaposed fluid filled cells each having a capillary extending to an orifice in the printing surface of the block, at least the part of the fluid in the capillary being ink, the orifices forming one and at most two single straight lines, means for filling the cells with ink, means for closing the cells completely except for said capillaries and means for exposing the so closed cells to a line of an infrared image.

45 5. A printing device according to claim 4 in which the fluid in the cells is partly the ink and partly gas and in which there is means for supplying ink to the capillaries other than through the gas-filled portions of the cells.

ALEXANDER MURRAY.
